UNITED STATES PATENT OFFICE.

HAROLD DEXTER BREWER, OF OKLAHOMA CITY, OKLAHOMA.

GAME BOARD.

Application filed November 5, 1923. Serial No. 672,901.

To all whom it may concern:

Be it known that I, HAROLD D. BREWER, a citizen of the United States, residing at Oklahoma City, in the county of Oklahoma and State of Oklahoma, have invented a new and useful Game Board, of which the following is a specification.

This invention relates to game boards and is designed primarily for use in playing 10 a game simulating the game of base ball and wherein the same methods of scoring can be utilized as in regular base ball games.

One of the objects of the invention is to provide a game board on which is outlined 15 a "diamond" and an "outfield" provided with recesses indicating the several playing positions and any one of which is adapted to receive a ball used as a game piece, thereby to indicate a "putout".

20 Another object is to provide a game board with a series of pockets suitably designated to indicate the results of different plays of the game piece.

A still further object is to provide novel 25 means whereby the game piece can be propelled by the player.

With the foregoing and other objects in view which will appear as the description proceeds, the invention resides in the combination and arrangement of parts and in the details of construction hereinafter described and claimed, it being understood that changes in the precise embodiment of the invention herein disclosed may be made 30 within the scope of what is claimed without departing from the spirit of the invention.

In the accompanying drawings the preferred form of the invention has been shown.

In said drawings

40 Figure 1 is a plan view of the game board showing the ball in position to be hit and showing one of the game pieces located at a base.

Fig. 2 is a section on line 2—2, Fig. 1.

45 Fig. 3 is a section on line 3—3, Fig. 1.

Referring to the figures by characters of reference 1 designates a flat board having an upstanding flange 2 along each edge thereof which constitutes an enclosure from 50 which the ball used in playing the game can rebound. Outlined on this board near one end is a "diamond" indicated at 3 and having representations of the usual bases 4, 5, and 6 and the home plate 7. A shallow recess 55 8 is formed in the home plate for receiving

a ball 9 of metal or other relatively heavy inert material. Located adjacent the base 4 is a recess 10 designated "First base". Two recesses 11 and 12 are located adjacent to and at opposite sides of the base 5 and are 60 designated, respectively, "Second base" and "Short stop". Another recess 13 is located near base 6 and is designated "Third base". Adjacent the center of the "diamond" is another recess 14 designated "Pitcher" while 65 located in the "outfield" portion of the board are side and central recesses 15, 16 and 17 designated, respectively "Left field", "Center field" and "Right field".

A transverse depression 18 is formed in 70 the top face of the board beyond the "outfield" depressions and that wall of this depression nearest the "diamond" is preferably concentric with the recess 8 in the home plate. Upstanding partitions 19 are located 75 in the depression 18 and extend longitudinally of the board, these partitions dividing the depression 18 into separate pockets. The relatively wide and deep pockets located adjacent the sides of the board and 80 which have been indicated at 20 are designated "Foul or strike". The central pocket 21 located directly back of the center field depression 16 is designated "Home run". Between this pocket and each of the pockets 85 20 are three pockets 22 designated, respectively, "1 base hit", "2 base hit", and "3 base hit".

Detachably and adjustably mounted on the game board 1 at one side of the "home 90 plate" 7 is a standard 23 having a base 24 through which is extended an attaching bolt 25. A clamping nut 26 engages this bolt and, when tightened, will hold the standard 95 against movement. Obviously by providing this connection the standard can not only be removed but can also be adjusted angularly relative to the board.

A laterally extending arm 27 is provided at the upper end of the standard and has a 100 depending stud 28 on which is mounted one end of the flexible tube 29 preferably formed of rubber. The other end of this tube is extended around and fastened to the small upper end of a bat 30 supported by the tube 105 with its lower end close to the game board and normally positioned directly back of the recess 8.

Mounted for rotation on studs 31 upstanding from the game board adjacent the stand- 110

ard 23 are dials 32, 33, 34, 35 and 36 movable relative to stationary indicators or pointers 37 on the game board. Dial 32 is suitably marked to indicate "Outs". Dial 5 32 is marked along the margin for use as a counter to indicate the number of runs made and is designated "Home team score". The dial 35 is similarly marked but is designated "Visitor's score". Dial 34 is provided with numbers adjacent the margin thereof to indicate "Innings" while dial 36 is marked to indicate "Strike".

In playing the game suitable movable game pieces are used one of these having 15 been illustrated at 38. These can be of any desired configuration and nine of them should be used by each player. In playing the game the regular base ball rules are followed. The ball 9 is placed in recess 8 20 and the first player draws the bat 30 away from the ball thereby placing the elastic tube 29 under tension. When the bat is released it will swing forward and hit the ball. If the ball lands in any one of the recesses 25 10 to 17 inclusive one "man" is "out". Should the ball land in either of the pockets 20 it would be counted as a strike and the same is true should the ball come to a stop on the game board outside of the pockets 30 and recesses. Should the ball be received by any one of the pockets 21 and 22 the "men" will be safe and will occupy the base indicated by the pocket in which the ball is received. The "runners" already on 35 bases will be advanced accordingly.

Score can be kept readily by manipulating the dials.

Obviously considerable skill can be de-

veloped in so manipulating the bat as to place the ball where desired.

40

What is claimed is:—

1. The combination with a game board having a "diamond" outlined thereon with a ball receiving recess in the "home plate", of a standard mounted on the board adjacent the recess, a resilient tube suspended from the standard, and a bat suspended from the tube.

45

2. The combination with a game board having a "diamond" outlined thereon with a ball receiving recess in the "home plate", of a standard mounted on the board adjacent the recess, a resilient tube suspended from the standard, and a bat suspended from the tube, there being separate depressions 50 in the game board remote from the recess for receiving a ball projected from the recess by the bat.

55

3. The combination with a game board having a "diamond" outlined thereon with a ball receiving recess in the "home plate", of a standard mounted on the board adjacent the recess, a resilient tube suspended from the standard, and a bat suspended from the tube, there being separate depressions 60 in the game board remote from the recess for receiving a ball projected from the recess by the bat, and counters mounted on the game board.

65

In testimony that I claim the foregoing 70 as my own, I have hereto affixed my signature in the presence of two witnesses:

HAROLD DEXTER BREWER.
Witnesses:

MARJORIE PALSON,
W. J. LANGON.
